(57) **CLAIM**

The ornamental design for a drinking bottle as shown and described.

DESCRIPTION

FIG. 1 is a top view of the drinking bottle.

FIG. 2 is a bottom view of the drinking bottle.

FIG. 3 is a front view of the drinking bottle.

FIG. 4 is a rear view of the drinking bottle.

FIG. 5 is a right side view of the drinking bottle.

FIG. 6 is a left side view of the drinking bottle.

FIG. 7 is a front, top, right side perspective view of the drinking bottle.

FIG. 8 is a front, top, right side perspective view of the drinking bottle with the carrying loop in an open position.

FIG. 9 is a front, top, right side perspective view of the drinking bottle with the lid and carrying loop in an open position; and,

FIG. 10 is a front, top, right side perspective view of the drinking bottle with the lid in an open position.

The broken lines show portions of the drinking bottle that form no part of the claimed design.

1 Claim, 3 Drawing Sheets
